US00D867061S

(12) **United States Design Patent** (10) **Patent No.:** **US D867,061 S**
(45) **Date of Patent:** **** Nov. 19, 2019**

(54) **BOTTLE CAP WITH L-SHAPED HANDLE**

(71) Applicant: **Can't Live Without It, LLC**, New York, NY (US)

(72) Inventors: **James Best**, Hewitt, NJ (US); **Clay Allen Burns**, New York, NY (US)

(73) Assignee: **CAN'T LIVE WITHOUT IT, LLC**, New York, NY (US)

(**) Term: **15 Years**

(21) Appl. No.: **29/666,154**

(22) Filed: **Oct. 10, 2018**

CPC B65D 39/00; B65D 39/16; B65D 42/00; B65D 42/02; B65D 43/32; B65D 43/02; B65D 43/16; B65D 43/22; B65D 43/26; B65D 45/04; B65D 50/00; B65D 50/02; B65D 51/005; B65D 51/007; B65D 51/14; B65D 51/145; B65D 51/18; B65D 51/28; B65D 51/16; B65D 51/242; B65D 51/243; B65D 51/2807; B65D 53/02; B65D 47/06; B65D 47/061; B65D 47/08; B65D 47/122; B65D 47/305; B65D 47/24; B65D 47/247; B65D 47/265; B65D 47/283; B65D 47/065; B65D 47/0866; B65D 47/0885; B65D 47/0871; B65D 47/0225; B65D 2543/00046; B65D 2543/00027; B65D 2543/00053; B65D 2543/00009; B65D 2539/00; B65D 41/00; B65D 41/02; B65D 41/04; B65D 41/0225; B65D 41/0233; B65D 41/06; B65D 41/12; B65D 23/108; B65D 23/001; B65D 35/46; B65D 81/3283; B65D 25/24; B65D 2251/0021; B65D 2251/0025; B65D 2251/0028; B65D 2251/0081; B65D 2251/0087; B65D 2251/009; B65D 2543/00231; B65D 23/104; B65D 1/0284; A47G 19/00; A47G 19/22; A47G 19/2205; A47G 19/2272; A47G 19/2266; A47G 19/2288; A47G 21/18; A47J 43/1087; A47J 43/27

(57) CLAIM

CLAIM

The ornamental design for a bottle cap with L-shaped handle, as shown and described.

DESCRIPTION

FIG. 1 is a perspective view of a first embodiment of a bottle cap with L-shaped handle showing our new design; FIG. 2 is a front elevational view thereof;

FIG. 3 is a rear elevational view thereof; FIG. 4 is a right-side elevational view thereof; FIG. 5 is a left-side elevational view thereof; FIG. 6 is a top view thereof; FIG. 7 is a bottom view thereof; FIG. 8 is a perspective view of the bottle cap with L-shaped handle of FIG. 1, showing the handle in an alternate position of use; FIG. 9 is a front elevational view thereof; FIG. 10 is a rear elevational view thereof; FIG. 11 is a right-side elevational view thereof; FIG. 12 is a left-side elevational view thereof; FIG. 13 is a top view thereof; FIG. 14 is a bottom view thereof; FIG. 15 is a perspective view of a second embodiment of a bottle cap with L-shaped handle; FIG. 16 is a front elevational view thereof; FIG. 17 is a rear elevational view thereof; FIG. 18 is a right-side elevational view thereof; FIG. 19 is a left-side elevational view thereof; FIG. 20 is a top view thereof; FIG. 21 is a bottom view thereof; FIG. 22 is a perspective view of the bottle cap with L-shaped handle of FIG. 15, showing the handle in an alternate position of use; FIG. 23 is a front elevational view thereof; FIG. 24 is a rear elevational view thereof; FIG. 25 is a right-side elevational view thereof; FIG. 26 is a left-side elevational view thereof; FIG. 27 is a top view thereof; and, FIG. 28 is a bottom view thereof.

Portions of features of the bottle cap with L-shaped handle not shown in the drawings form no part of the claimed design. The broken lines represent parts of the article that form no part of the claimed design.
